UNITED STATES PATENT OFFICE

2,505,929

LOAD TRANSFER DEVICE

Ray Cyrus Yeoman, Lufkin, Tex., assignor to
Texas Foundries, Inc., Lufkin, Tex., a corpora-
tion of Texas

Application March 19, 1945, Serial No. 583,500

3 Claims. (Cl. 94—8)

1

This invention relates to load transfer devices and more particularly to devices for transmitting loads between adjacent slabs of concrete or the like.

One of the objects of the invention is to provide a load transfer device which will maintain the slabs in vertical alignment and which will limit relative separation of the slabs.

Another object is to provide a load transfer device made up of complementary members to be imbedded in the slabs respectively and which are connected for relative movement through one or more pins.

Still another object is to provide a load transfer device in which yielding material is arranged between the pins and the members to cushion relative movement thereof.

A further object is to provide a load transfer member in the form of a sinuous strip having its rebent portions so arranged that they will interlock with complementary portions of adjacent strips.

The above and other objects and advantages will be more readily apparent from the following description when read in connection with the accompanying drawing in which—

Figure 1 is a partial vertical section through a pair of adjacent slabs connected by a load transfer device embodying the invention;

Figure 2 is a partial horizontal section on the line 2—2 of Figure 1;

Figure 3 is a perspective view of a part of one of the strips;

Figure 4 is a view similar to Figure 1 of an alternative construction; and

Figure 5 is a horizontal section on the line 5—5 of Figure 4.

As shown in Figures 1 and 2, adjacent slabs 10 and 11 of concrete or the like are arranged with a filler strip 12 between their adjacent faces to close the space therebetween against ingress of water or the like. The filler strip 12 may be made of any desired type of yielding material such as asphalt saturated felt, compressed wood or metallic expansion joint structures. Preferably the filler strip is formed by two separate strips spaced apart in the central portion of the slab to leave a space through which load transfer devices may extend.

The slabs are connected by a load transfer mechanism including identical metallic strips 13. The strips 13 are formed of relatively flat elongated strips of metal sinuously bent to provide rebent portions 14 and 15. The rebent portions 14 along one side of the member are formed with

2

central slots 16 and the portions 15 are reduced in width to substantially the same width as the slots. Preferably the portions 15 are slightly narrower than the slots so that they will enter the slots in a complementary member snugly. Vertical movement is thus held to minimum without preventing the limited horizontal movement.

In forming a joint between the adjacent slabs, two strips 13 are employed and are imbedded in the slabs respectively as shown in Figures 1 and 2 with the rebent portions along one side of each member projecting from the face of the slab. As shown, the rebent portion 14 of one member projects from one of the slabs while the narrow portion 15 of the other member projects from the opposite slab so that the portions 15 may pass through the slots 16 to define vertical openings between the members. With this construction, a vertical load on either of the slabs will be transmitted to the other slab through interengagement of the rebent portions 15 with the sides of the slots 16. In this way the slabs are maintained in the same plane so that they will provide a smooth upper surface.

To limit separation of the slabs, pins 17 of smaller diameter than the openings between the members are mounted in the openings and preferably have enlarged heads 18 to limit movement thereof through the openings. In order to cushion the relative movement between the slabs and members sleeves 19 of yielding material, such as rubber or asphalt compositions, are arranged around the pins substantially to fill the openings.

As the slab faces tend to separate when the slabs contract under low temperatures, the members 13 tend to move apart to reduce the size of the openings defined by the rebent portions 14 and 15. This action squeezes the yielding material 19 and if continued to a sufficient extent will squeeze the yielding material to the extent of its compressibility or may actually cause the rebent portions of the members to engage the metal pins 17. At this time, further separation of the slab faces will be prevented so that the slabs cannot move out of contact with the filler strips 12 to break the seal at the joint. It will be understood that the filler strips and load transfer members are so designed that they will accommodate the maximum expected separation of the slab faces in response to changes of atmospheric conditions.

To provide for movement of the slab faces toward each other when the slabs expand, yielding plastic material 20 such as rubber, asphalt composition or the like is placed between the pro-

jecting portions of the strips and the opposite slab faces. This material may be placed in any desired manner but is advantageously secured to the strips to be held properly in place during installation. When the concrete is in plastic form the material 20 holds it out of direct contact with the metal of the strips and will yield when the slabs expand to permit their adjacent faces to move closer together.

Another construction embodying the invention is illustrated in Figures 4 and 5 for connecting adjacent slabs of concrete 21 and 22 which have an expansible filler strip 23 between their adjacent faces. In this construction, identical plate members 24 are imbedded in the slabs in a vertical position and may if desired be formed with openings 25 therethrough to assist in anchoring them in the slabs. The openings may be formed by partially punching out portions of the plates to leave anchoring fins as shown. The edge portions of the plates project beyond the respective slab faces and interfit as shown in Figure 4 so that they will transmit vertical loads between the slabs to maintain the upper surfaces thereof in the same plane.

In order to limit separation of the slab faces, the serrations on the projecting edges of the slabs are rolled around as shown at 26 to form registering openings through the serrations. A pin 27 of smaller diameter than the openings extends through the openings and is preferably surrounded by a sleeve 28 of yielding material which substantially fills the openings. Movement of the slab faces together is provided for as in Figures 1 and 2 by yielding plastic material 29 overlying the outer ends of the serrations.

In use this construction operates in substantially the same manner as that of Figures 1 to 3. As the slab faces tend to separate the yielding material 29 will be squeezed until it has been compressed to its maximum extent or until the serrations 26 engage the pin 27 after which no further separation of the slab faces is possible.

While two embodiments of the invention have been shown and described in detail herein, it will be understood that these are illustrative only and are not intended as definition of the scope of the invention, reference being had for this purpose to the appended claims.

What is claimed is:

1. In combination with adjacent slabs of concrete or the like a load transfer device comprising a pair of sinuous strips imbedded in the slabs respectively with angularly rebent portions

thereof projecting beyond the faces of the slabs, part of the projecting portions being formed with central slots therethrough and the other rebent portions being of a width to extend through the slots to define openings between the strips, and pins of smaller diameter than the openings fitting through the openings.

2. In combination with adjacent slabs of concrete or the like a load transfer device comprising a pair of sinuous strips imbedded in the slabs respectively with angularly rebent portions thereof projecting beyond the faces of the slabs, part of the projecting portions being formed with central slots therethrough and the other rebent portions being of a width to extend through the slots to define openings between the strips, pins of smaller diameter than the openings fitting through the openings, and sleeves of yielding material around the pins substantially filling the openings.

3. In combination with adjacent slabs of concrete or the like a load transfer device comprising a pair of sinuous strips imbedded in the slabs respectively with angularly rebent portions thereof projecting beyond the faces of the slabs, part of the projecting portions being formed with central slots therethrough and the other rebent portions being of a width to extend through the slots to define openings between the strips, pins of smaller diameter than the openings fitting through the openings, the outer surfaces of the rebent portions being covered with yielding plastic material.
